(57) **CLAIM**

The ornamental design for a compartmented food package as shown and described.

DESCRIPTION

FIG. 1 is a perspective view of a compartmented food package incorporating the design of the present invention; FIG. 2 is a perspective view thereof, in which certain flaps are in a partially opened configuration; FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a top view of the compartmented food package of FIG. 2, in which certain flaps are in the partially opened configuration; and,

FIG. 9 is a bottom view of the compartmented food package of FIG. 1.

1 Claim, 9 Drawing Sheets
